United States Patent Office

Des. 186,798
Patented Dec. 1, 1959

186,798

ROCKET HEAD

Leo Y. Booharin, San Francisco, Calif.

Application April 30, 1958, Serial No. 50,677

Term of patent 7 years

(Cl. D71—1)

FIG. 1

FIG. 2

FIG. 3

Fig. 1 is a side elevational view of the rocket head of my design.

Fig. 2 is a bottom plan view of the rocket head of Fig. 1.

Fig. 3 is a top plan view of the rocket head of Fig. 1.

I claim:

The ornamental design for a rocket head, substantially as shown.
